[57] CLAIM

The ornamental design for a smoking device, as shown and described.

DESCRIPTION

FIG. 1 is a bottom plan view of a smoking device, showing my new design;

FIG. 2 is a top plan view thereof;

FIG. 3 is a side elevational view, the opposite side being a mirror image thereof;

FIG. 4 is a longitudinal sectional view taken along line 4—4 of FIG. 2;

FIG. 5 is an end elevational view thereof;

FIG. 6 is an elevational view of the end opposite that shown in FIG. 5.
